PUNCHING MACHINE

Edward J. Von Pein, Dayton, Ohio, and Paul J. Schlessiger, Endicott, N. Y., assignors to International Business Machines Corp., New York, N. Y., a corporation of New York

Application August 15, 1939, Serial No. 290,260

16 Claims. (Cl. 164—115)

This invention concerns punching machines, particularly of the type in which key controlled, or duplicate punching operations, skipping and cut-out of duplicating operations, may be effected, and has for its general object the provision of certain improvements whereby the different functions previously performed under manual selection or control, or by the use of specially formed elements, may be dispensed with and such functions may be performed under a new form of control and elements and in accordance with the predetermined manner of operation of the machine.

In the tabulating card punching machine art, it is the common practice to provide a punching machine which, under control of keys, is adapted to designate statistical data on tabulating cards, and in carrying out punching operations it is also necessary from time to time to commonly duplicate on a series of cards the data represented on a so-called "master" card. Machines for effecting such duplicating operations are also well known and shown in many prior patents.

It is at times undesirable to effect duplicating punching operations for certain fields of the master card and such duplicating punching operations have heretofore, been prevented or cut out under control of the so-called "cut-out" mechanism.

It is also at times desirable to effect the skipping of one or more card columns of the card to be operated upon since such columns may have previously been punched and this may be effected either under control of the repeated operation of a skip key or alternatively, by the provision of a so-called "skip" bar.

In machines disclosed in the prior art, the cut-out and skipping functions have been effected under control of metal bars which, upon an order, are formed at the factory so as to take care of certain requirements in punching cards. For each different type of punching operation a different form of skip bar for effecting either cut-out or skipping operations was required. It is obvious that in order to take care of the varied requirements for punching cards a number of these expensive bars were required to be on hand, each formed differently so as to meet the different punching requirements.

It occasionally happened that, in order to take care of a certain requirement which came up unexpectedly and without advance notice, there was not at hand a skip or cut-out bar which would control the machine in the desired manner.

Rather than hold up the procedure of punching

cards in accordance with the desired requirement until a new bar was obtained, the punching machine had to be operated in an inefficient manner. In order to skip certain card columns it was necessary to repeatedly operate the skip key and, correspondingly, for effecting the cut-out of the duplicating operations certain other expedients had to be utilized, and in each case the speed of operation of punching machine was greatly reduced, and its operation performed in a less efficient manner. The main object of the present invention is to provide an improved form of means, whereby the cut-out and the skipping operations, as well as other functions of the punching machine, may be predetermined solely by perforations in a control card inserted in the machine. Such relatively inexpensive control card is similar in form to the ordinary tabulating card and with the new arrangement the punching machine itself is utilized to effect the perforating of the control card at any desired time so as to cause the punching machine to carry out the different functions in accordance with some predetermined plan. The positioning of this control card in the punching machine will automatically condition certain controlling mechanisms so that the different functions of the punching machine may be effected automatically, and without attention of the operator.

A still further object, with respect to the analysis of the control card, is to provide an improved form of analyzing mechanism which is capable of analyzing the card at rest and which also includes a correlated step by step column read-out mechanism whereby electrical controlling circuits may be made under control of the column read-out mechanism in accordance with the previous analysis of the control card. The above arrangement avoids the necessity of passing over the control card analyzing brushes which are operated step by step, and which would rapidly damage or tear the perforations in the control card as the latter was analyzed by the repeated analysis of the brushes passing over the card itself.

More specifically, considering sub-combinations of the present improvements, it is one object of the present invention to provide a skipping mechanism for a card carriage which is initiated in operation under control of a perforation in a control card, and to terminate the skipping operation under control of a perforation in a succeeding card column of the same control card.

The last-mentioned object is carried out by

- providing an electrical relay system which includes a magnet, the energization of which elevates the usual holding pawl of the escapement mechanism permitting the card carriage to escape. In accordance with the succeeding perforation of the control card another relay is effective which blocks the movement of the card carriage and effectively locks it in the position to which it is skipped.
- 10 Certain other improvements incorporated in the relay system of the skipping mechanism are for the purpose of providing an efficient operation of the improved skipping mechanism, so that such operations may be efficiently performed and exactly in accordance with the predetermined plan.
- Another object of the present invention is to provide a novel electrical control system for the duplicating mechanism of the punching machine, 20 and wherein the initiation of the duplicating function may be performed under control of an initial perforation in the control card and may be terminated by a succeeding perforation in the same control card. By reversely arranging the 25 perforation in the control card the sequence of operation may be varied, and by the provision of this flexible relay system duplicating and cut-out of the duplicating operations may be effected in a predetermined sequence.
- 30 Still another object of the present invention is to provide means, which preferably acts upon the completion of the last function performed with respect to the last card field, so that the parts utilized in this last function are restored 35 to normal thereby conditioning at this time all of the parts to normal, to enable the initial function which is performed on the first card field of the succeeding card to be performed in a more efficient manner. In the present form of 40 machine a limited time is available for conditioning such parts to normal and for initiating the first function on the first card field of the succeeding card, and it is preferable to condition all the parts operated to normal before the card carriage is positioned to the first card column 45 position.

It is understood that while it is preferable and desirable to incorporate in a single machine all of the novel features shown herein, certain of 50 the features may be used separately in a punching machine of the form shown herein, or even incorporated in punching machines of other types. The utilization of all of the novel features provides a flexible machine which may be 55 considered universal with respect to the different and predetermined requirements of punching systems.

In certain other requirements all of the features may not be required and such features 60 may be used separately and isolated from the others.

It is, therefore, to be understood that the preferred embodiment of the invention shown herein is merely illustrative and should not be considered as restrictive.

Other objects of the invention will be pointed out in the following description and claims and illustrated in the accompanying drawings, which disclose, by way of example, the principle of the 70 invention and the best mode, which has been contemplated, of applying that principle.

In the drawings:

Fig. 1 is a plan view of a well known form of punching machine in which the present improvements are preferably incorporated.

Fig. 2 is a plan view of a control card employed in connection with the present invention and which is shown perforated in selected columns so as to effect the operation of certain mechanisms which initiate the different functions of the 5 punching machine.

Fig. 3 is a plan view of the analyzing mechanism for the control card shown in Fig. 2 and also shows at the left hand end of this figure the electrical apparatus for effecting the stopping and locking of the punch carriage when the latter is skipped.

Fig. 4 is a cross sectional view taken through the analyzing mechanism on the line 4-4 of Fig. 3 and shows its coordination with certain 15 parts of the punching machine.

Fig. 6 is a view similar to Fig. 5 but shows the 20 parts in normal position.

Fig. 7 is a view in side elevation of the electrical apparatus for controlling the cut-out of the duplicating operation and is taken on the line 7-7 of Fig. 1.

Fig. 8 is a view in side elevation of the 25 electrical apparatus for initiating the carriage skipping operations.

Fig. 9 is a wiring diagram showing the electrical connection of the electrical instrumentalities employed in connection with the present invention.

Fig. 10 is a sectional view of a part of a punching machine of a well known form.

ANALYZING MECHANISM

There will now be described the construction of the analyzing mechanism which is adapted to analyze the control card designated 10 in Fig. 2. The present machine is adapted to perform four different functions with respect to a card and in order to select or determine the functions to be performed as the successive card fields are to be operated upon, the analyzing mechanism pre-analyzes the card 10 to thereby control such functions. Since four different functions are capable of being carried out by selection, a corresponding number of horizontal rows are appropriated, which at the intersecting selected vertical card columns receive perforations to initiate the operation of certain means so as to cause the machine to function in a certain way. The manner in which these different functions are carried out under control of the control card 10 will be further explained as the specification progresses.

The construction of the analyzing mechanism is best shown in Figs. 3, 4, 5 and 6 to which special reference should be made. In general, the analyzing mechanism comprises a lower stationary contact unit and an upper movable analyzing unit. The assembled analyzing mechanism is carried by a plate 11 (Figs. 3 and 5) which is attached by screws 12 to the frame 9 (Fig. 5) of the punching machine. The plate 11 is adapted to carry, in addition to the analyzing mechanism, certain other parts forming part of the present improvements.

The lower unit of the analyzing mechanism comprises a base 13 of insulating material which is formed, as best shown in Figs. 3 and 4, at its 70 ends with integral card guides 14 which are separated to an extent corresponding to the horizontal dimension of the control card 10, so that by the cooperation of the guides 14 with the shorter marginal edges of the control card the 75

latter will be properly guided and located with respect to the analyzing elements. For the purpose of making desired adjustments of the card analyzing mechanism with a column selecting mechanism to be later described, the base 13 is attached to the plate 11 by means of adjusting screws 15 (Figs. 3 and 5) which pass through slots 16 in the base 13. The upper surface of the base 13 is recessed at each slot 16, as designated by reference numeral 17, so that the head of the screw 15 will project beneath the upper surface of the base 13, thereby preventing interference with the control card 10 when the latter is manually inserted in the analyzing mechanism.

15 As best shown in Fig. 4, there is embedded in the base 13 a plurality of contact bars 18, there being one bar for each card column except the first card column, and for a reason which will be obvious as the construction is better understood. The left ends (Fig. 4) of the series of contact bars 18 are flush with the corresponding edge of the base 13 so that, by a suitable column contact making mechanism, contact with the bars 18 may be successively made. It should also be mentioned that the base 13 carries a common current conducting bar 19, which is best shown in Figs. 4 and 5, and the bar 19 forms part of the contact making unit which includes the contact bars 18.

30 In order to provide a stop for the control card when the latter is manually positioned in the analyzing mechanism, the base 13 carries a stop plate 20 (Fig. 4), preferably of insulating material, and the latter is engaged by one of the longer edges of the control card so as to suitably locate the latter in the analyzing unit. As best shown in Fig. 5 a card operated lever 21 is pivotally carried by a bracket attached to the base 13 and the upper extension 22 of the lever 21 moves in a slot 23 of the card stop 20. It is obvious that when the control card 10 is positioned as shown in Fig. 5 it will engage the portion 22 of the card lever 21 thereby rocking the latter so as to close card lever contacts 24. In Fig. 5, the control card 10 is shown in its proper analyzing position and having operated the card lever 21 the contacts 24 will be closed. The card lever 21 is so positioned that when the control card is placed in the analyzing unit, with its printed 50 face downward, the rearward right side corner of the control card will cooperate with the card lever 21 and actuate the same.

The movable analyzing unit is carried by a pair of parallel supporting frame plates 25, each of 55 which is carried by the base 13. The movable contact unit comprises two U-shaped plates 26 and 27 which are joined at their ends by assembly screws 27a thereby providing a unitary frame structure. Interposed between bars 28 of insulating material are four contact plates 29 each of which is provided with a series of contact fingers 30. The fingers 30 are so positioned that they are adapted to pass through the perforations of the card 10 of the four lower horizontal rows of 60 perforations and passing through such perforations make contact with the bars 18 which are positioned directly beneath the contact fingers 30, as best shown in Fig. 3. A series of assembly bolts 31 are provided to assemble the bars 28, contact plates 29 and plates 26 and 27 so that the contact plates 29 may be supported and be carried by the frame comprising the U-shaped plates 26 and 27.

In order that the analyzing unit may be rocked 75 downwardly from the normal position shown in

Fig. 6 to the position shown in Fig. 5, and then slightly to the left so that the contact fingers 30 will make positive connection with the bars 18 through the perforations, the following means is provided and the description will be given in connection with the arrangement shown in Fig. 5 since the construction is duplicated for both ends of the movable analyzing unit. As best shown in Fig. 5, the side plate 32 of the U-shaped plate 26 carries rollers 33 and 34, the roller 34 co-operating with an elongated slot 35 formed in the side plate 25 and the roller 33 cooperates with an elongated slot 36 which is elongated both in vertical and horizontal dimensions for a reason to be subsequently apparent.

15 The side plates 25 form the bearings for a rock shaft 37 which at its midpoint is provided with an operating handle or lever 38. The rod 37 carries at each end a cam 39. With the parts in the normal position shown in Fig. 6 it is obvious that by rocking the shaft 37 by the handle 38 in a clockwise direction, the cooperation of the cam 39 with an extension 40 of the plate 32 will cause the analyzing unit to be rocked about the axis of the roller 34 as a pivot. This operation is effected because a spring 41 is extended between a spring supporting pin 42 carried by the plate 25 and a spring supporting pin 43 carried by the side plate 32, the springs 41 at both ends being of sufficient strength to normally hold the analyzing unit in the position shown in Fig. 6. The upward normal position of the analyzing unit with the contact fingers 30 out of cooperation with the control card 10 is effected by means of a spring 44 which extends between the spring supporting pin 43 and a supplemental pin 45 also carried by the plate 25. The spring 44 is of sufficient strength to hold the analyzing unit in the upward normal position shown in Fig. 6.

30 Therefore, as the shaft 37 is rocked clockwise by the lever 38 the analyzing unit will be rocked until the roller 33 strikes the horizontal edge of the slot 36. A further rocking of the shaft 37 by the lever 38 will cause a projection 46 of the cam 39 to be brought into engagement with the extremity of the extension 40 to laterally move the analyzing unit to the left, as viewed in Fig. 5, or in a forward direction in the machine, and such movement will be effected until the movable 35 analyzing unit is in the position shown in Fig. 5.

The first tilting movement of the analyzing unit will cause the contact fingers 30 to pass through the perforations located at the junctions of the vertical card columns and the four lower 50 horizontal rows. The subsequent lateral movement of the analyzing unit will cause the contact fingers to scrape over the contact bars 18 thereby making firm contact therewith and this operation is enabled due to the fact that the perforations are rectangular or oblong, as is best shown in Fig. 2.

55 Due to the tendency of the spring 44 to upwardly elevate the right end of the analyzing unit and the tendency of spring 41 to move the unit to the right it will be seen that primarily on account of the weight of lever 38 which will overcome this combined action the extremity of the projection 46 will be maintained in locking cooperation with the extension 40 and thus maintain the analyzing unit in the position shown in Fig. 4 so that continuous electrical contact may be maintained through the perforations of the control card, and such condition will be maintained until the handle 38 is reversely rocked to bring the movable 70 75

analyzing unit out of analyzing position to enable the insertion of the next control card 10.

CARD PUNCHING MACHINE

5 The card punching machine, in which the present improvements are preferably incorporated, is well known and fully shown and described in the patent to F. Lee and G. F. Daly, No. 1,976,618, dated October 9, 1934, and only so much of the 10 operation thereof will be explained as is necessary for an understanding of the operation in connection with the present invention.

There will now be described, in a general way, the operation of the key controlled punching machine whereby such punching operations may be affected.

In general, referring to Fig. 10, the punching machine includes a card supply magazine 50, (see also Fig. 1) from which cards are fed singly from 20 the bottom by means of a picker knife 48 (Fig. 1) of a well known form, and which, as described in the aforementioned Patent No. 1,976,618, feeds the cards to a position beneath the series of card punches 51 with the first column of the card in 25 position to receive the perforation. From this position, if manual punching operations are to be effected on the first and succeeding card columns as in the present example, a card is engaged by a pusher 52 (Fig. 10) mounted on an escapement 30 rack 53 which, under control of a conventional escapement mechanism shown in the top of Fig. 8, permits the advance of a card step by step for successive card punching operations.

The escapement mechanism, shown in Fig. 8 35 and just referred to, is of the same general type as that disclosed in the patent to Schaaff, No. 1,426,223 dated August 15, 1922, and the aforementioned patent to Lee et al., No. 1,976,618 also gives a full description of the construction and 40 operation of this escapement mechanism.

A series of keys 54, shown in Figs. 1 and 10, are adapted to select the punches for actuation, and the operation of each key, as is well known, will effect the shifting of an interposer 55 (Fig. 10) 45 which rocks a bail 56 about its pivot 57, elevating link 58 to close contacts 95, and which latter contacts correspond to similarly designated contacts in Patent No. 1,976,618. This, as explained in the aforementioned patent, and by a circuit to be 50 later described herein is adapted to cause the energization of a magnet 49 (corresponding to a similarly designated magnet in Patent No. 1,976,618) which, through its armature 61 and link and bell crank connections 62, is adapted to 55 draw downwardly a punch bar or plate 63 to force the selected interposer 55 against the related punch 51 thus perforating the card. The escapement mechanism thereby operates to feed the card carriage a distance of a hole step of the card.

60 In general, after each card column is manually punched, the carriage escapes to the next card column position and this operation is repeated until the selected card field is completely punched in all of its card columns.

SKIPPING OF CARD FIELDS

Another function of the machine is to permit the automatic skipping of a selected card field of the card 50 when such skipping mechanism is effective. This function is also under control of the control card 10. The purpose of such skipping is to cause the card carriage to be moved by one jump and without the necessity of punching the ordinary "skip" key. Such card fields are usually 75 gang punched to represent like data in the series

of cards and since they are already punched, time will be saved by omitting operations in such card fields by skipping operations of the nature just described.

One form of apparatus for effecting the skipping of selected card fields is fully shown and described in the patent to H. L. Read, No. 1,962,750 dated June 12, 1934, and in view of the full disclosure of this form of mechanism only a general description will be given herein. This mechanism 5 includes a bar which is carried by the escapement rack and which is provided with suitable notches and cam surfaces which through intermediate mechanism is adapted to elevate the stepping dog 65 (Fig. 8) to release the escapement rack and 10 the card carriage. The card carriage will thereupon skip over the columns or fields which are 15 not to be punched. The aforementioned skipping mechanism may be automatically effective upon the carriage reaching a predetermined column by 20 manual punching operations, or alternatively, by the depression of the usual skip key which is the "X" (Fig. 1) or "11" index point position key. As will be more fully described hereinafter, in contradistinction to the all-mechanical and manually 25 controlled skipping mechanism shown in the patent to Read, No. 1,962,750 the present improvements incorporate a skipping mechanism which is under electrical control, and may be selected for 30 operation under control of perforations in the horizontal card column No. 1, as disclosed in the control card 10 in Fig. 2.

DUPLICATING MECHANISM

Machines of the type herein shown are provided, as is the present machine, with a duplicating mechanism which is adapted to automatically duplicate from a master card M (Fig. 1) certain data thereon and punch a representation of this data in a selected card field. In the present 40 machine, this function is automatically initiated, as will be subsequently described in connection with an example, under control of selected perforations in the horizontal row No. 4 of the control card 10, shown in Fig. 2. The duplicating mechanism is also old and is fully shown in the patent to F. Lee et al., No. 1,976,618 and in view of the full disclosure in this patent only a general description will be given herein of this part of the mechanism.

The master card M, referring to Fig. 1, is placed in position between arms 70 attached to and extending from the escapement rack 53 so that the master card will advance step by step with the new card being prepared.

When a predetermined field of the master card M is correlated with the analyzing brushes 68 (see Fig. 9) the perforation at the card column which is to control duplication, and succeeding columns, will permit an electrical contact to be 60 made between the related analyzing brush 68 and a contact roll 69 thereby causing the energization of an associated selector magnet 60.

Referring to Fig. 10, it will be noted that the energized selector magnets 60 will attract their 65 armatures and thereby rock arms 71 which have mechanical connections to the keys 54. Consequently, the energization of the selector magnet 60 will cause a punching operation in the same manner as if the related key 54 was depressed.

This duplicating mechanism is more fully described in the aforementioned patent to Lee et al., No. 1,976,618, and the reference numerals 60, 68 and 69 in Fig. 9 indicate elements similarly designated in the last mentioned patent.

COLUMN CUT OUT

Referring to Fig. 2, it will be noted that horizontal row No. 3 is utilized to initiate another function of the machine, which is the cutting out of the duplicating operation when a predetermined card field is to be operated upon. Such cut out functions may occur either before or after a duplicating operation to cut out the duplication of data on a field of the master card M so as to permit, if desired, punching under control of the keys 54. This has, heretofore, been accomplished by the opening of contacts 135 (see Fig. 9), and which contacts correspond to similarly designated contacts in Patent No. 1,976,618.

The prior construction for cutting out the duplicating action included a bar which is carried by the escapement rack and which was provided with low and high portions so as to cause the closing and opening of the contacts 135 when predetermined card fields come into operation. This prior art construction is fully shown in Figs. 12, 13 and 14 of the aforementioned patent to Lee et al., No. 1,976,618.

As will be more fully described as the specification progresses, the present machine includes a novel electrical control means whereby a similar function may be effected without requiring the use of the so-called "high and low" bar.

OPERATION OF THE MACHINE

The general operation of the machine will now be explained in connection with a specific example to indicate the various steps involved in the punching of a card which requires the use of the four different functions previously described.

It should be understood that the present example is merely illustrative and that the operations for different cards may be varied in accordance with the different requirements. This is particularly true since the present control means are flexible in their selection which permits operations of the machine to be altered and varied in sequence in accordance with the different requirements.

The control card shown in Fig. 2 illustrates one form of control in which the different functions of the machine may be carried out in the following manner:

Key punching operations	Columns 1 to 11
Card carriage skipping operation	Columns 12 to 21
Key punching operations	Columns 22 to 70
Cut out of the duplicator	Columns 71 to 76
Duplication of data on master card	Columns 76 to 80

The manner in which the functions of the machine are carried in the above sequence will now be described.

Referring to the circuit diagram (Fig. 9), when current is applied to the line wires 100 and 101, a circuit is made as follows: from the positive line side 100 to contacts 136, which correspond to similarly designated contacts as shown in Fig. 1 of Patent No. 1,976,618, and also Fig. 10 herein, the circuit extending through such contacts since they are normally closed, to contacts 147, and which correspond to similarly designated contacts in Patent No. 1,962,750, by a wire 102 to a relay magnet 80, thence through card lever contacts 24 which are now closed since it is assumed that the control card is in analyzing position and the movable analyzing unit has been operated, and

from said contacts to the duplicator cut-out contacts 135, to the negative line side 101. The energization of the magnet 80 will cause the closure of relay contacts 80b thereby connecting the negative line side 101 to certain parts of a column 5 contact making mechanism to be subsequently described in detail. The circuit extends from the negative line side 101 to contacts 135, through card lever contacts 24, through relay contacts 80b now closed, and by wire 103 to the common 10 conducting bar 19, which is also shown in Figs. 4 and 5 and which has previously been referred to.

Contacts 147 are retained closed to retain relay magnet 80 energized but are opened after the 15 carriage is located in the last card column, as explained in Patent No. 1,962,750.

As best shown in Figs. 1 and 3, the arms 70 which carry the master card M also carry a plate 104 provided with ratchet teeth 105. The right 20 end of the plate 104 carries insulated therefrom a bracket 106 (Figs. 3 and 5) which carries a pair of brushes 107 and 108. The brush 107 makes continuous contact with the common conducting bar 19 and the brush 108 makes successive contact with the ends of the bar 18, as will be clearly understood by reference to Fig. 5.

It was previously pointed out, and as is also shown in Fig. 9, no bar 18 is provided for the first column and when the card carriage is in the 30 first card column punching position, the circuit from the negative line side 101 to the brushes 107-108 is open. In the present example, it is assumed that key punching operations are effected for the first eleven card columns and the desired keys 54 will be successively depressed so as to effect card punching operations in such columns. Referring to Fig. 9, it will be seen that the circuit for punching operations extends from the positive line side 100, through contacts 136, 40 through contacts 95 which are closed by any of the punch keys to the magnet 49, which is thereby energized to effect punching operations, and thence to the negative line side 101.

Since the carriage which carries the card to 45 be punched, and also the master card, are moved step by step, it is obvious that the contact brushes 107-108 will make contact successively with the bars 18. When a punching operation is effected for the 11th column, the card carriage will, after 50 a punching operation, escape to the 12th column. At this time a circuit connection will be made in the following described manner.

Since the related contact finger 30 of the contact plate 29 of the horizontal row No. 1 makes contact with the perforation at the 12th card column, the previously described circuit will be extended by the contact finger 30 and the contact bar 18 to a wire 137 (Fig. 9) and thence through normally closed contacts 138, to a magnet 109 and by a wire 110 to contacts 136, which are now closed, and from these contacts to the line side 100, thereby causing the energization of the start to skip control magnet 109.

The start to skip control magnet 109 and associated electrical parts are disclosed in Fig. 8 wherein it will be seen that the magnet 109 is supported by a bracket 110 carried by a vertically arranged base plate 112 which, in turn, is attached to the frame of the punching machine. 70 The armature 113 of the magnet 109 is pivoted by a stud 114 carried by the plate 112. The free end of the armature 113 underlies the resilient contact blade 115 of contacts 116, the resiliency of the contact plate 115 causing the free 75

end of the armature to abut against an adjustable screw 117. The adjusting screw 117 is carried by a bracket 118 which is carried by the plate 112.

- 5 A push rod 119 is slidable in the bracket plates 110 and 118 and the upper and lower portions of the push rod 119 are coupled together by a screw coupling member 120, the purpose of which is to decrease or increase the length of the push rod 10 to effect a desired adjustment of the latter. The push rod 119 is mounted, therefore, for vertical operation and in the position shown in Fig. 8 which is the normal position, the coupling member 120 normally rests upon the free end of the armature 113. The upper extremity of the push rod 119 underlies a lug 121 which is an integral offset of the stepping dog or holding pawl 65, it being clear that when the push rod 119 is elevated the holding pawl 65 will be elevated so as 20 to be disengaged from the teeth of the escapement rack 53 thereby permitting the carriage to be freely moved.

When the contact bar 18 of column 12 card is engaged by brush 108 the magnet 109 is energized 25 as previously described, thereby attracting its armature 113 and closing contacts 116 at substantially the time the holding pawl 65 is disengaged from one of the teeth of the escapement rack 53. The card carriage carrying the card to be worked upon, as well as the master card, is thereby free to be moved under control of the usual spring operated drum employed in card punching machines of this type. The means for moving the card carriage by such spring operated 30 means is well known and is fully shown and described in Fig. 17 of Patent No. 1,772,186, dated August 5, 1930.

From Fig. 8, it will be seen that the armature 113 is provided with a downwardly bent latching lug 122 and said lug normally engages the upper end of an armature 123 of a magnet 124. As best shown in this figure the normal latching of the armature 123 causes the closure of the contacts 138 which, it will be recalled, permit 40 the energization of the magnet 109. When the armature 113 is fully retracted, due to the complete energization of the magnet 109, the lug 122 will be fully disengaged from the upper extremity of the armature 123 causing a spring 123a 45 to rock the armature 123 so that its upper end is beneath the lug 122. This will latch contacts 116 closed and also hold pawl 65 in disengaged position. The rocking of pawl 65 to disengaged position occurs substantially at the time contacts 50 55 116 closed and also the push rod 119 has elevated the holding pawl 65 to disengaging position. Therefore, contacts 138 are not opened to deenergize magnet 109 until the card carriage is unlatched, the magnet 109 is completely energized, 60 and also contacts 116 are closed. The opening of the contacts 138 will thereby cause the deenergization of the magnet 109 permitting the arc due to the break of the circuit to be taken by contacts 138 instead of the contact bar 18 and 65 brush 108.

The closure of contacts 116, as best shown in Fig. 9, will cause a circuit to be closed from the positive line side 100, contacts 136, to a wire 125, to a relay magnet 126, through the contacts 116 70 now closed, a wire 127, to a wire 159, to the negative line side 101, thereby causing the energization of the magnet 126 and the closure of relay contacts 126a.

The punch carriage will now escape freely until the perforation in the 22nd column of the

second horizontal row is rendered effective which will, by means now to be disclosed, stop the operation of the skipping mechanism and condition the machine so that key punching operations or duplicating operations may be effected on column 22 and succeeding card columns. 5

The closure of relay contacts 126a will effect a closure of a circuit which leads from the positive line side 100, through control contacts 136 now closed, a wire 129 to the magnet 124, from 10 said magnet to a stop-skip control magnet 130 through relay contacts 126a to the contact plate 29 associated with the second horizontal row of the control card (see Fig. 2), the related contact bar 18 associated with the 22nd card column, the brush 108, brush 107, contact bar 19, wire 103, relay contacts 80b, card lever contacts 24, duplicator cut-out contacts 135 to the negative line side 101. It is obvious, therefore, that the above mentioned circuit is closed to effect the energization of the magnets 124 and 130 when the card carriage has skipped to the 22nd card column. At this time, as will now be described, mechanism which causes the stopping of the card carriage at the 22nd card column position will now 25 be effective. This mechanism is best shown in Fig. 3 at the left hand portion thereof.

A base plate 139 is adapted to carry parts of the stop-skip mechanism and said base plate has attached thereto a bracket 140 which carries the 30 aforementioned magnet 130 and which may be termed a "stop-skip control magnet." The armature 131 of the magnet 130 is pivoted on a stud 132 carried by the base plate 139. The armature 131 is provided with a downwardly extending carriage stop extension 133 and a spring 134 extended between the extension 133 and the bracket 140 maintains the stop extension 133 against an adjusting screw 142. By means of the adjusting screw 142 the armature 131 is adjusted to its desired normal or attracted position. 35

As shown in Fig. 3, the stop extension 133 is adapted to cooperate with the ratchet shaped teeth 105 of the plate 104 and said stop extension should be maintained in such a normal position so that it is free of the ratchet teeth 105 to permit the free movement of the card carriage. The means for effecting this desired relationship comprises an adjusting means now to be described in detail. The base plate 139 is attached to the plate 11 by means of a screw 143 and the base plate 139 may be pivotally adjusted about the screw 143 so as to effect the desired relationship between the stop extension 133 and the 50 ratchet teeth 105. Carried by the plate 11 is a square stud 144 which is riveted to the plate 11, the stud 144 passing through a hole 145 in the base plate 139. An adjusting screw 146 is received by a square stud 148 which is riveted to the plate 139 and the adjusting screw is in engagement with the stud 144. By turning the adjusting screw 146, the plate 139 will revolve around the shoulder of the screw 143 and when the desired adjustment has been made the plate 55 60 65 70 75 80 85 90 95 100 105 110 115 nism, the card carriage will be positively stopped after it has escaped a distance of the predetermined columns.

In order to latch the armature 131 in its attracted or carriage stopping position, the following described means is provided: The armature 131 is provided with a depending portion which upon the attraction of the armature is received by a shoulder 151 of a latch which is formed as a bell crank pivoted on plate 139, and comprising an arm 152 which is provided with the shoulder 151, and an arm 153 to which a spring 154 is secured. The spring 154 maintains the arm 153 against a collar 155 which is attached to an operating rod 156, and which in the position shown in Fig. 3 is prevented from moving to the right. It is obvious that when the armature 131 is attracted, the depending portion thereof will be caught by the shoulder 151 thereby latching the armature 131 in such position that the stop extension 133 will be maintained in locking relationship with one of the ratchet teeth 105 thereby positively holding the carriage in its stopped position and preventing its rebound.

From the wiring diagram (see Fig. 9), it will be noted that the magnet 124 is energized at the same time as magnet 130 because it is in electrical series connection therewith. However, the magnet 130 operates faster than the magnet 124 so that the carriage will be stopped before the complete energization of the magnet 124 has been effected. After the card carriage has been stopped, the attraction of the armature 123 (see Fig. 8) of the magnet 124 will cause the upper end of the armature 123 to be withdrawn to the left out of cooperation with the latching lug 122 thereby closing contacts 138 and causing said contacts to be relatched in closed position, as shown in Fig. 8.

The above described operation will, of course, permit the push rod 119 to drop downwardly to cause the holding pawl 65 to reengage with the escapement rack 63 and, furthermore, permit contacts 116 to open to deenergize the relay magnet 126 which opens its relay contacts 126a to cause the deenergization of magnets 124 and 130. However, the armature 131 of magnet 130 will remain in latched position.

It occasionally happens when certain fields are to be skipped and for such fields the master card M contains perforations in one or more columns to be skipped, that such duplicating operations should not be effected. From the wiring diagram shown in Fig. 9, it would be seen that the circuit from the elements of the duplicator which comprise magnet 60, brushes 68, common contact roll 69, extends through normally closed contacts 91, and also contacts 128. The contacts 128 correspond to contacts shown in Fig. 11 of the Patent 1,976,618, dated October 9, 1934, which are designated by the same reference numeral. As more fully described in the last mentioned patent, contacts 128 are opened by the rocking of the pawl 114 (and which corresponds to the pawl 65 herein) and the opening of these contacts will open the circuit to the duplicator brushes. In the present machine, since the pawl 65 will be maintained in its rocked or elevated position during the skipping of predetermined columns, it is obvious that the contacts 128 will be retained open thereby preventing duplicating operations for card columns which are skipped, if such card columns contain perforations.

It will be assumed for the present that the next stage in the operation of the machine consist in

manual punching operations to punch the representation of data in column 22 and succeeding card columns, it being observed that the carriage has been positively stopped at the 22nd card column position.

For punching in the 22nd card column position, one of the keys 54 (Fig. 10) is manually depressed to effect a punching operation in the manner previously described. By the operation of one of the keys 54, contacts 195 (Figs. 9 and 10) are closed and such contacts correspond to similarly designated contacts in Fig. 2 of the patent to F. Lee et al., No. 1,976,618. The closure of the contacts 195 will effect the closure of the circuit from the positive line side 100, through contacts 136, 15 through contacts 195 now closed, a resistance R, a magnet 158, which may be termed a release magnet, and a wire 159 to the negative line side 101, thereby causing the energization of the release magnet 158. The energization of the magnet 158 concurrent with a card punching operation, will attract its armature 159 (Fig. 3) and since the latter abuts the right end of push rod 156, the latter will be moved to the left. Since the collar 155 engages the arm 153, the bell crank 25 which comprises the arm 153 and the arm 152 will be rocked counter-clockwise about its pivot thereby disengaging the shoulder 151 from the armature 131. Spring 134 is now effective to rock the armature to bring the stop extension 133 out of engagement with the ratchet teeth 105 of the plate 104 thereby freeing the carriage so that its step by step movement may be placed under control of the regular escapement mechanism, shown at the top of Fig. 8.

It will be noted that the card carriage now escapes from the 22nd card column position to the 23rd card column position and the brush 108 is now disengaged from the bar 18 correlated with the 22nd card column position thereby opening 40 at this point the circuit which includes the relay contacts 126a. It should be noted, however, that the opening of the circuit at this point did not effect the deenergization of magnets 124 and 130 and which would result in arcing at the bar 18 45 and brush 108. This cannot happen because of the fact that when contacts 116 (Figs. 8 and 9) were previously opened, the relay magnet 126 was deenergized to cause the opening of the relay contacts 126a, and which caused the deenergization of the magnets 124 and 130. It will be seen, therefore, that the opening of the circuit to the magnets 124 and 130 is effected by the previous opening of relay contacts 126a and these are of such dimension so as to withstand without deterioration the arcing due to the breaking of the circuit which includes these two magnets. This operation is preferable instead of breaking the circuit by the bars 18 and the brush 108.

Successive manually operated card punching 60 operations may ensue until the carriage reaches the 71st card column position at which time another function will take place. Of course, if the card columns comprising card column 22 and ensuing card columns of the master card M contain perforations, it will be obvious that upon reaching the 22nd card column position, duplicating operations will be automatically effected with operations taking place as just described. Such duplicating operations will take place until 70 the 71st card column is reached, at which time the cut out device of the duplicator will be effective so as to prevent duplicating operations of the perforation in the 71st and succeeding card columns of the master card M. The manner in 75

which such cut out operations are performed will now be described in detail.

Upon effecting a punching operation in the 70th column, either by a manual punching operation or by an automatic duplicating operation, the card carriage is skipped to the 71st card column position and upon the brush 108 (Fig. 8) encountering the bar 18 correlated with the 71st card column, a circuit will be closed which is described as follows. This circuit is from the negative line side 101, through the duplicator cutout contacts 135 now closed, card lever contacts 24 now closed, relay contacts 80b now closed, wire 103, common current conducting bar 19, brush 107, brush 108, the bar 18 correlated with the 71st column, a related contact finger 30, the contact plate 29 of horizontal row No. 3, a wire 161, contacts 162, magnet 163, contacts 136, to the positive line side 100. The closure of this circuit will effect the energization of the magnet 163 since contacts 162 are normally closed.

Referring now to Fig. 7, it will be seen that the energization of the magnet 163 will attract its armature 164 so as to close contacts 92 and open contacts 91. Contacts 92 will be latched in closed position by the engagement of a bent lug 164a with the lower extremity of an armature 166 of a magnet 165. The attraction of the armature 164 to latching position will also permit the opening of contacts 162, thereby opening the circuit to the magnet 163 and causing its deenergization, although the armature 164 thereof will remain in latched position, as well as the closure of contacts 92. The opening of the contacts 162 to effect the deenergization of the magnet 163 causes the arc, due to the breaking of circuit of magnet 163 to be taken by the contacts 162 instead of the brush 108 when the latter moves to the 72nd card column position, concomitant with a key controlled card punching operation in this column.

Referring now to the top of the wiring diagram in Fig. 9, it will be seen that the opening of contacts 91 open the circuit to the duplicator so that if there was a perforation in the 71st card column of the master card no duplicating operation would be effected for this column on the card to be operated upon. This, of course, is also true for succeeding card columns since contacts 91 remain in latched open position.

Since no duplicating operations will be effected, the card to be operated upon will be manually punched and the card carriage will escape step by step. When the card is punched in the 75th column, the regular escapement mechanism will permit the carriage to escape to the 76th card column and a circuit is closed which is described as follows: from the positive line side 100 to relay contacts 136, contacts 128, contacts 92, wire 167 to the magnet 165, a wire 168 to the contact plate 29 associated with the horizontal row No. 4, through a contact finger associated with the 76th card column, through the perforation at such card column of the control card 10 shown in Fig. 2, to the contact bar 18 related to the 76th card column, brush 108, brush 107, wire 103, relay contacts 80b, card lever contacts 24, duplicator cutout contacts 135 now closed, to the negative line side 101. The aforementioned circuit will cause the energization of the magnet 165, and as shown in detail in Fig. 7, will attract its armature 166 thereby unlatching the armature 165 to permit the closure of contacts 91 and the opening of contacts 92. In this operation, the contacts 162 will again be closed to condition

the circuit which includes the magnet 163 for subsequent closure. The closure of contacts 92 will close the circuit to the duplicating brushes 68 and since it is assumed perforations are present in the master card M in columns 76 to 80, duplicating operations will be effected on the card to be punched for such card columns.

When the card carriage occupies the last card column position contacts 150 are closed and contacts 147 are opened and such contacts correspond to similarly designated contacts shown in Figs. 7 and 13 of the patent to Read, No. 1,962,750 and which operation is fully explained therein.

The present machine is also provided with a card ejecting mechanism, designated by the reference numeral 169 in Fig. 1, and also a power driven carriage return and card feeding mechanism so that the carriage is returned and a new card is fed to the carriage after the punched card has been ejected. These mechanisms are also well known in the art and are fully shown and described in the patents to Lee and Daly, No. 1,976,618; F. M. Carroll, No. 1,970,600 and H. L. Read, No. 1,962,750 and for this reason are only generally shown herein. The card ejecting mechanism shown in Fig. 1 is set in operation by the closure of contacts 150 which cause, by the circuit shown in Fig. 9, the energization of a magnet 199, and which magnet corresponds to a similarly designated element in Patent No. 1,976,618. As more fully described in the last mentioned patent, the energization of this magnet causes the operation of the card ejecting mechanism which, in turn, causes the closure of contacts 201 in the same manner as the similarly designated contacts disclosed in Patent No. 1,976,618. The closure of the contacts 201 will effect the energization of the magnet 175, which also corresponds to a similarly designated magnet in Patent No. 1,976,618. The magnet 175 is also shown in Fig. 10 and upon its energization, it will attract its armature so as to cause the opening of contacts 136 and the closure of contacts 190. The closure of contacts 190 will set a motor 157 into operation which will return the card carriage to its first card column position, as well as the master card, and also effect the operation of the card feeding mechanism so that a new card is fed to the card carriage.

The above operation is briefly explained herein since it is well known in the art.

FIRST COLUMN CONTROL SWITCH

In the illustrative machine when the card carriage is returned after a punching cycle the carriage will be returned and stopped in the first card column punching position, and when the card carriage is positioned at the first card column an insufficient time is available for causing both the restoration of those parts which were utilized in the performance of the last function on the preceding card operated upon and the setting of parts which initiate the initial function on a succeeding card. It is preferable, therefore, in view of the limited time available to effect the restoration of such parts to provide mechanism acting before the card carriage is at the first card column position and which conditions all of the parts to normal so that such parts are available to function immediately at the time the carriage is at the first card column position. This is attained, in the preferred embodiment, by a so-called "first column control switch." This switch is shown in Fig. 1 and the

- switch arm thereof is identified by the reference numeral 170 and is positionable to four different positions; namely, "skip," "punch," "duplicate," and "cut-out." The switch arm 170 is 5 also diagrammatically shown in Fig. 9 and comprises, as shown in this figure, a switch arm 170 which may be selectively positioned in operative correlation with four contact points, which are identified by letters designating the function 10 which is selected at the different positions of the switch arm 170. The switch arm 170 is normally in the position "P" in which manual punching operations are to be effected for the first card field. In order to understand the function of the 15 switching mechanism just referred to, several examples will be explained indicating how it cooperates with other parts of the machine so as to attain the desired mode of operation.
- 20 1. *Last card field skipped, followed by manual punching of first card field of the next card*

It will be assumed that the last card field was to be skipped and that the first card field of the next card is to be manually punched.

- 25 Recalling the previous description, it will be observed that under control of a perforation in the horizontal row No. 1 of the control card 10 a circuit was closed, at the beginning of the card field to be skipped, to a magnet 109. From Fig. 8, it will be noted that the energization of magnet 109 caused the latching of contacts 116, and the closure of such contacts caused the energization of the relay magnet 126 and the closure 30 of relay contacts 126a, and such relay contacts, due to the latching of contacts 116, are retained closed during the skipping of the carriage corresponding to the card field to be skipped. When the card carriage reaches the 80th card column position, or the last column position of the card 35 carriage, contacts 147 are opened thereby opening the circuit to the relay magnet 80, since this circuit extends from the positive line side 100, contacts 136 now closed, contacts 147 now open, relay magnet 80, card lever contacts 24 now closed, and duplicator cut-out contacts 135, now 40 closed. The deenergization of the magnet 80 will cause the closure of the relay contacts 80c when the card carriage is at the 80th card column position, and a circuit will now be closed; from the positive line side 100, through relay contacts 45 136, magnet 124, magnet 130, relay contacts 126a now closed, to the switch point designated "P," switch arm 170, the relay contacts 80c, a wire 171 to card lever contacts 24, and duplicator cut-out contacts 135 to the negative line side 101.

- 45 It will be recalled that the energization of the magnet 130, referring to Fig. 3, will cause the stopping of the card carriage at the 80th card column position. At the same time magnet 130 is energized, the magnet 124 is also energized so as to cause the opening of contacts 116 which effects the deenergization of the relay magnet 126 and thus, the opening of contacts 126a to effect the deenergization of the magnet 130. 50 However, it will be recalled that the stop extension 133 (Fig. 3) will be latched in such position so as to latch the carriage in the 80th card column position. However, in the operation of the machine now being described, the stop extension 133 is later unlatched due to the fact that when the magnet 80 was deenergized at the 80th card column position a circuit was closed which is described as follows: from the positive line side 100, a wire 173, to relay contacts 80a, a wire 174, 55 to the resistance R, the magnet 158, and thence

by the wire 159 to the negative line side 101. Magnet 158 is a larger magnet than magnet 130 and receives its complete energization after magnet 130 is fully energized.

It is clear, therefore, that due to the above 5 relationship the magnet 158 will be later effective to unlatch stop extension 133. When magnet 158 is completely energized it will rock bell-crank 152-153 to unlatching position, and at the same time the rod 156 will rock armature 10 131 and assisted by the spring 134 (Fig. 3) will cause the stop extension 133 to be moved out of the 80th card column position of the card carriage, and unlocking the latter so that it may 15 be returned to the first card column position.

It is noted that the above described operation is carried out at the 80th card column position of the carriage thereby restoring all of the parts which were utilized in the skipping of the last 20 card field to their normal positions and conditioning the machine so that initial card punching operations may be effected for the first card field of the next card to be operated upon.

2. *Manual punching of last card field, skipping of first card field of next card* 25

In the event that the last card field is punched by manual punching operations and the first card field of the next card to be operated upon should be skipped in the first card field, the 30 switch arm 170 is positioned to the "skip" position in which position the switch arm is adjacent the contact point designated "S" in Fig. 9. Upon punching the last card column, the positioning of the carriage to such card column position will 35 open contacts 147, as previously described, to thereby effect the deenergization of the relay magnet 80 causing the closure of relay contacts 80c, as previously described. A circuit will now be closed from the negative line side 101, through 40 card lever contacts 24, to relay contacts 80c, to the switch arm 170, the switch point designated "S," and by the wire 131 to contacts 138, thence from such contacts to the magnet 109, to a wire 110, and thence to contacts 136 now closed, to the 45 positive line side 101. This will effect the energization of the magnet 109, and, as will be recalled, will, by the controlling mechanism shown in Fig. 8, elevate the pawl 65 and latch it in elevated position. The card carriage is then 50 returned by power to the first card column position and when it is in such position, it will immediately be skipped to the extent of the card field which is to be skipped.

It is obvious, therefore, that if the first card 55 field is to be skipped the mechanism for initiating this function will be set into operation when the last card column of the carriage has been reached.

3. *Cut-out of duplicator for last card field and 60 duplicate for first card field of next card*

Another type of operation comprises the operation in which the cut-out of the duplicator is effected for the last card field of a card and then 65 duplicating operations for the first card field of the next card is to be effected. In this type of operation, since a duplicating operation is to be effected for the first card field, the switch arm 170 will be positioned to the "duplicate" position, 70 and in such case the switch arm 170 will be adjacent the switch point designated "D" in Fig. 9.

It will be recalled for cut-out operations that the initiation of such operations is effected by the energization of the magnet 163 which will 75

latch contacts 91 in open position, and contacts 92 in closed position and such condition of the contacts will be maintained to the last card column position of the card carriage. At this time as has been described, magnet 80 will be de-energized and relay contacts 80c will close the circuit leading from the negative line side 101, through duplicator cut-out contacts 135, card lever contacts 24, relay contacts 80c, switch arm 170, contact point designated "D," a wire 168 to a magnet 165, thence by a wire 167 to contacts 92 now closed, to contacts 128, thence to contacts 136 to the positive line side 100. This will effect the energization of the magnet 165 thereby unlatching the armature 164 of magnet 163 permitting contacts 91 to close and opening contacts 92.

It is obvious by the circuit connection just described that the closure of contacts 91 will render the duplicating mechanism operative for the first card field of the succeeding card to be operated upon.

4. Punching of last card field, cut-out of duplicator for first card field of next card

Another form of operation would be punching the last card field, either under control of the keys or by a duplicating operation, and then causing for the first card field of a succeeding card the cut-out of the duplicating operations under control of the first card field of the master card M. Since the first card field operation is to be a cut-out operation, the switch arm 170 is positioned so that it is adjacent the designation "Cut-out," Fig. 1, and in such position the switch arm 170 will be adjacent the switch point designated "CO" in Fig. 9.

As previously described, the circuit will be extended from the switch arm 170 to the last mentioned switch point, and thence by a wire 161 to contacts 162, thence to a magnet 163, then to contacts 136, and to the positive line side 100. This will cause the energization of the magnet 163 thereby latching contacts 92 in closed position and contacts 91 in open position. This will set the controlling parts for the cut-out mechanism so that the duplicating operations for the first card field will be cut-out, thereby permitting manual punching operations for the first card field of the next card to be operated upon.

DISABLING OF CARD ANALYZER DURING RETURN OF CARRIAGE

When the card carriage is restored from the 80th card column position to the first card column position, the brushes 107 and 108 will, of course, also make contact with the respective bar 19 and the contact bars 18 in succession, thereby attempting under control of the perforations in the control card to effect the energization of the controlling magnets. However, fraudulent circuit closing is prevented during the return of the card carriage to the first card column position by the opening of contacts 136 and such contacts remain open until the first card column position of the carriage is reached. The manner in which the contacts 136 are retained open is fully shown and described in the aforementioned patent to Lee, No. 1,976,618, and also in Fig. 10 herein. The intermediate blade of the contacts 136 and 190 carries a block 186 of insulating material which is caught by a shoulder of a bell crank 187 when the armature 175 is energized to close contacts 190 and open contacts 136. By means of the latching bell crank the contacts 136 are re-

tained open until said bell crank is actuated by means, fully disclosed in Patent No. 1,976,618 and fully described therein, so as to permit the closure of contacts 136 and the opening of contacts 190 when the card carriage is at the first card column 5 position.

While there has been shown and described and pointed out the fundamental novel features of the invention as applied to a single modification it will be understood that various omissions and 10 substitutions and changes in the form and details of the device illustrated and in its operation may be made by those skilled in the art without departing from the spirit of the invention. It is the intention, therefore, to be limited only as 15 indicated by the scope of the following claims.

What is claimed is:

1. In a punching machine capable of effecting in sequence manual punching operations, duplicating operations, the cut out of duplicating 20 operations, and the skipping of a card carriage to omit manual punching operations, the combination with a card carriage, of an escapement mechanism therefor for positioning the carriage step by step for manual punching operations, a 25 skip control means for said carriage comprising means to unlock said carriage to enable said carriage to be released for positioning to another card field, a duplicating mechanism including a control means for rendering the duplicating 30 mechanism effective, and a supplemental control means for rendering the duplicating mechanism ineffective, means for analyzing a control record having at predetermined columns thereof control perforations for selectively controlling 35 the operation of the aforesaid control means, and column selector means controlled by the columnar position of said carriage and cooperating with said analyzing means for selectively bringing into operation each of the aforesaid control means to 40 condition the machine so as to automatically effect selectively, manual punching operations, skip or cut out operations, or duplicating operations at predetermined positions of the carriage and in accordance with the perforations in the 45 control record.

2. In a punching machine in which duplicating operations are effected or manual punching operations are effected by a step by step position of said carriage, the combination with a card 50 carriage, of an escapement mechanism for said carriage for positioning said carriage step by step for manual punching operations or duplicating operations, a skip control means for disabling said escapement mechanism to enable said 55 carriage to be released for positioning to another card field, a duplicating mechanism including control means to render said duplicating mechanism effective and control means for rendering said duplicating mechanism ineffective, means for analyzing a record at rest having perforations arranged in columns and at predetermined columnar positions for selectively bringing selected control means into operation, and means 60 cooperatively related with said analyzing means and operated by said carriage for rendering as said carriage is moved step by step the perforations effective to bring the aforementioned and related control means into selective operation at the predetermined columnar positions of the carriage and in accordance with the columnar positions of the perforations on the record.

3. An automatically operated punching machine in which work cards are punched in accordance with a predetermined plan comprising, 75

5 a key controlled punching mechanism including a carriage and an escapement mechanism controlling the step by step position of said carriage, means for feeding work cards from a supply stack to a carriage of said punching mechanism, a skipping mechanism comprising control means to render the escapement mechanism ineffective to enable the release and stopping of the carriage to a predetermined card column position 10 of the work card, a duplicating mechanism comprising means under control of a pattern card for controlling the operation of the punching mechanism to duplicate data on the work card from fields of a pattern card, control means to render 15 said duplicating mechanism effective to duplicate data derived from a certain field of the pattern card on the work card and duplicator cut out control means to render the duplicating mechanism ineffective for duplication of data from other fields of the pattern card, selecting means 20 dependent upon the position of said carriage for causing the automatic operation of the aforesaid control means to condition the machine in an automatic sequence for manual punching operations, duplicating operations, cut out of duplicating operations, or skipping of the carriage, and means automatically effective upon terminating the last operation of the machine upon a work 25 card for causing the operation of the feeding means to feed a new work card to said carriage and to cause a selected control means to be effective to condition the machine for the first operation to be performed in connection with the new work card.

30 4. In a punching machine for selectively effecting duplicating punching operations, manual punching operations, and skipping of one or more card fields of a work card, the combination with a key controlled punching mechanism for punching 35 said work card and including a carriage and an escapement mechanism therefor for causing the movement of the carriage step by step during successive punching operations, of a duplicating mechanism controlling the operation of the punching mechanism for duplicating on a work card data derived from a pattern card, a skipping mechanism including control means for operating the escapement mechanism to release 40 the carriage and supplemental control means controlling said escapement mechanism for enabling said escapement mechanism to stop said carriage, control means for rendering the duplicating mechanism effective and a supplemental 45 control means for rendering said duplicating mechanism ineffective to terminate duplicating operations, means for analyzing a record having perforations for controlling all of the aforesaid control means, means controlled by the analyzing 50 55 60 65 70 75

means for causing in accordance with the position of the carriage the perforations to effect the operation of the related control means to condition the machine in sequence for manual punching operations, skipping of a predetermined card field, rendering the duplicating mechanism effective for punching a card field of the work card and for causing the duplicating mechanism to be cut out for a selected card field of the pattern card, means for selecting one of the aforesaid control means to be initially effective for conditioning the machine for operation upon the first card field of a new work card in accordance with the particular control means selected, and means operative upon positioning of said carriage in the first card column position of the work card to

cause the selected control means to be effective.

5 5. In a punching machine for selectively effecting duplicating punching operations on a work card from a pattern card, skipping of card fields of a work card, and cutting out duplicating operations for certain fields of the pattern card, the combination with a punching mechanism including a carriage and an escapement for causing the movement of the carriage step by step during successive duplicating punching operations, of a duplicating mechanism controlling the operation of the punching mechanism for punching on the work card data derived from the pattern card, a skipping mechanism including control means for operating the escapement mechanism to release the carriage and supplemental control means for enabling said escapement mechanism to stop said carriage at its released position, control means for rendering the duplicating mechanism effective and a supplemental control means for rendering said duplicating mechanism ineffective to terminate duplicating operations, means for analyzing a record having perforations for controlling all of the aforesaid control means, means controlled by the analyzing means for causing in accordance with the position of the carriage the perforations to effect the operation of the related control means to condition the machine in sequence for manual punching operations, skipping of a predetermined card field, rendering the duplicating mechanism effective for punching a card field and for causing the duplicating mechanism to be cut out for a selected card field of the pattern card, means for selecting one of the aforesaid control means to be initially effective for conditioning the machine for operation upon the first card field of a new work card and in accordance with the control means selected, and means operative upon positioning of said carriage in the first card column position of the new work card to cause the selected control means to be effective.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990

- tral means selected, and means operative upon positioning of said carriage in the first column position of the new work card to cause the selected control means to be automatically effective.
5. An automatically operated punching machine in which work cards are punched in accordance with a predetermined plan comprising, a key controlled punching mechanism for punching card fields of a work card, means for automatically feeding work cards from a supply stack to said punching mechanism, a skipping mechanism comprising control means to render the punching mechanism ineffective for punching predetermined card column positions of a work field, 10 a duplicating mechanism comprising means under control of a pattern card for punching fields of the work card to duplicate data derived from fields of said pattern card, control means to render said duplicating mechanism effective to duplicate data 15 on a certain field of the pattern card on the work card and duplicator cutout control means to render the duplicating mechanism ineffective for duplication of data from other fields of the pattern card, selecting means for causing the automatic operation 20 of the aforesaid control means to condition the machine in an automatic sequence for manual punching operations, duplicating operations, cut out of duplicating operations, or the operation of the skipping mechanism for 25 the different fields of the work card, and means automatically effective upon terminating the last operation of the machine upon a work card for causing the operation of the feeding means to automatically feed a new work card to said carriage.
- 30 35. An automatically operated punching machine in which work cards are punched in accordance with a predetermined plan comprising, a key controlled punching mechanism including a card carriage and an escapement mechanism controlling the step by step position of said carriage, means for feeding work cards from a supply stack to the carriage of said punching mechanism, a skipping mechanism comprising control means to render the escapement mechanism ineffective to enable the release and stopping of the carriage to a predetermined card column position, a duplicating mechanism comprising means under control of a pattern card for controlling the operation 40 of the punching mechanism to duplicate data on the work card from fields of a pattern card, control means to render said duplicating mechanism effective to duplicate data derived from a certain field of the pattern card on the work card and duplicator cutout control means to render the duplicating mechanism ineffective for duplication 45 of data from other fields of the pattern card, selecting means dependent upon the position of said carriage for causing the automatic operation of the aforesaid control means to condition the machine in an automatic sequence for manual 50 punching operations, duplicating operations, cut out of duplicating operations, or skipping of the carriage, manual means for selecting a control means to be effective for the first field of a work 55 card, means automatically effective upon terminating the last operation of the machine upon a work card for causing the operation of the feeding means to feed a new work card to said carriage, and means to cause in accordance with the 60 control means selected by said manual means the selected control means to be effective to condition the machine for the first operation to be performed in connection with the new work card.
- 65 7. An automatically operated punching machine in which work cards are punched in accordance with a predetermined plan comprising, a key controlled punching mechanism for punching a work card in one or more fields thereof, a skipping mechanism comprising electrical control means to render the punching mechanism ineffective to punch the card at a predetermined field, a duplicating mechanism comprising means under control of a pattern card for effecting punching operations on the work card to duplicate data on the work card from fields of a pattern card, control 70 means to render said duplicating mechanism effective to duplicate data derived from a certain field of the pattern card on the work card, selecting means dependent upon the position of said carriage for causing the automatic operation of the last named control means to automatically condition the machine for duplicating operations, and means automatically effective upon terminating either the duplicating operation or key controlled punching operations upon a work card 75 for causing upon the sensing of a perforation in a record apart from the work card or pattern card the electrical control means to be effective to thereby prevent punching of the work card in said predetermined card field by either the key controlled punching mechanism or the duplicating mechanism.
8. An automatically operated punching machine in which work cards are punched in accordance with a predetermined plan comprising, a key controlled punching mechanism, means for feeding work cards from a supply stack to a card carriage of said punching mechanism, escapement means for positioning said carriage step by step concomitant with punching operations, a skipping mechanism including electrical control means to render the escapement means ineffective to enable the release of the carriage to a predetermined card column position, an electrical duplicating mechanism comprising means under control of a pattern card for controlling the operation of the punching mechanism to duplicate data derived from the pattern card on the work card, electrical control means to render said duplicating mechanism effective to duplicate data derived from a certain field of the pattern card on the work card and to render the duplicating mechanism ineffective for other fields of the pattern card, selecting means dependent upon the position of said carriage for causing the automatic operation of the aforesaid electrical control means to condition the machine for manual punching operations, duplicating operations, or skipping of the carriage automatically and in a predetermined sequence, and means automatically effective upon terminating the last operation of the machine upon a work card for causing the operation of the feeding means to feed a new work card to said carriage and to cause the automatic operations of the selected electrical control means which is to be effective for the first operation upon the new work card.
9. An automatically operated punching machine in which work cards are punched in accordance with a predetermined plan comprising, a key controlled punching mechanism for punching a work card in one or more fields thereof, a skipping mechanism comprising electrical control means to render the punching mechanism ineffective to punch the card at a predetermined field, a duplicating mechanism comprising means under control of a pattern card for effecting punching operations on the work card to duplicate data on the work card from fields of a pattern card, control means to render said duplicating mechanism effective to duplicate data derived from a certain field of the pattern card on the work card, selecting means dependent upon the position of said carriage for causing the automatic operation of the last named control means to automatically condition the machine for duplicating operations, and means automatically effective upon terminating either the duplicating operation or key controlled punching operations upon a work card for causing upon the sensing of a perforation in a record apart from the work card or pattern card the electrical control means to be effective to thereby prevent punching of the work card in said predetermined card field by either the key controlled punching mechanism or the duplicating mechanism.

10. An automatically operated punching machine in which work cards are punched in accordance with a predetermined plan comprising, a key controlled punching mechanism, means for feeding work cards from a supply stack to a card carriage of said punching mechanism, escapement means for positioning said carriage step by step concomitant with punching operations, a skipping mechanism including electrical control means to render the escapement means ineffective to enable the release of the carriage to a predetermined card column position, an electrical duplicating mechanism comprising means under control of a pattern card for controlling the operation of the punching mechanism to duplicate data derived from the pattern card on the work card, electrical control means to render said duplicating mechanism effective to duplicate data derived from a certain field of the pattern card on the work card and to render the duplicating mechanism ineffective for other fields of the pattern card, selecting means dependent upon the position of said carriage for causing the automatic operation of the aforesaid electrical control means to condition the machine for manual punching operations, duplicating operations, or skipping of the carriage automatically and in a predetermined sequence, and means automatically effective upon terminating the last operation of the machine upon a work card for causing the operation of the feeding means to feed a new work card to said carriage and to cause the automatic operations of the selected electrical control means which is to be effective for the first operation upon the new work card.

11. An automatically operated punching machine in which work cards are punched in accordance with a predetermined plan comprising, a key controlled punching mechanism, means for feeding work cards from a supply stack to a card carriage of said punching mechanism, escapement means for positioning said carriage step by step concomitant with punching operations, a skipping mechanism including electrical control means to render the escapement means ineffective to enable the escapement of the carriage to a predetermined position, a duplicating mechanism

comprising means under control of a pattern card for controlling the operation of the punching mechanism, control means to render said duplicating mechanism effective to duplicate data 5 derived from a certain field of the pattern card on the work card and to render the duplicating mechanism ineffective for other fields of the pattern card, record controlled selecting means dependent upon the position of said carriage for 10 causing the automatic operation of the aforesaid control means to condition the machine for manual punching operations, duplicating operations, or skipping of the carriage in a predetermined sequence, means automatically effective 15 upon terminating the last operation of the machine upon a work card for causing the operation of the feeding means to feed a new work card to said carriage, means to restore the control means utilized for the last operation upon 20 the work card to normal condition from its operated condition, means to cause the selected control means to be effective for the first operation upon the new work card, and means separate from said record controlled selecting means 25 for selecting the control means to be effective for the first operation upon the new card.

12. In an apparatus for punching cards to duplicate data derived from a pattern card in different card fields of a work card, the combination with a punching mechanism, of an electrical duplicating means controlled by said pattern card for controlling the operation of the punching mechanism to effect the duplication of data on the work card derived from different 30 card fields of the work card, means comprising a relay to initiate the operation of the punching mechanism under control of the electrical duplicating means, a supplemental relay for cutting out the operation of the punching mechanism under control of the duplicating means, means for analyzing a perforated record to determine the position of the work card for initiating duplicating operations and for determining the position of the work card for terminating duplicating operations, and means under control of said analyzing means to cause the first mentioned relay to be effective to initiate duplicating operations, and means operable at a predetermined position of the carriage to cause the last mentioned relay to terminate duplicating operation.

13. In an apparatus for punching cards to record data in different card fields, the combination with a card punching mechanism, of an electrical duplicating mechanism controlled by a pattern card for controlling the operation of the punching mechanism to duplicate data derived from the pattern card on the work card, means comprising a relay and contacts thereof for controlling the duplicating circuits of said duplicating mechanism, said contacts being normally closed so as to cause the duplicating mechanism to be normally operative for duplicating operations, and means operable at a predetermined 60 position of the work card for causing the energization of said relay for causing the latter to open the related contacts thereby rendering the duplicating mechanism ineffective.

14. In a punching machine, the combination of 70 a punching mechanism including a carriage, a duplicating mechanism comprising means under control of a pattern card for causing the opera-

tion of said punching mechanism to duplicate data derived from the pattern card on a work card, means for analyzing a perforation on a record apart from the pattern or work card representing the columnar position said carriage is 5 to be in when duplicating operations are to be initiated, manually controlled means for controlling the operation of said punching mechanism to punch said work card step by step, and means cooperatively related with said analyzing 10 means and operable in accordance with the position said carriage is in when manual punching operations are terminated and when said perforation is analyzed for causing the operation of electrical control means under control of the analyzing 15 means to effect the automatic operation of said duplicating mechanism.

15. In a punching machine in which successive manual punching operations are effected during a step by step position of a card carriage, an escapement mechanism for said carriage for enabling said carriage to be escaped, step by step, concomitant with manual punching operations, a control means for said escapement mechanism for disabling the latter to enable the card carriage to be skipped, a control means for subsequently enabling said escapement mechanism to stop the carriage after said carriage has been skipped to a predetermined position, means for analyzing perforations located at predetermined 30 columnar positions of a control record for controlling the operation of said control means, and means operated by said carriage for causing one of said perforations to effect the operation of the first named control means at a predetermined 35 position of the carriage to initiate the skipping of said carriage, and for causing said other perforation to effect when the carriage has been skipped a predetermined number of columns the operation of the second named control means to 40 cause the stopping of said carriage after it has been moved to skip a predetermined number of columns.

16. In a punching machine in which duplicating operations are effected and manual punching operations are effected by a step by step position of said carriage, the combination with a card carriage and an escapement mechanism therefor, of a key controlled punching means to punch a work card and for operating said escapement mechanism to enable a step by step position of said carriage, a duplicating mechanism, a control means therefor for rendering said duplicating mechanism effective and a supplemental control means for rendering said duplicating mechanism subsequently ineffective, analyzing means for analyzing a record provided with perforations at predetermined columnar positions, means operable concomitantly with the step by step position of said carriage for causing when successive manual punching operations are completed one of said perforations at a predetermined columnar position to render the first named control means effective to automatically initiate duplicating operations, and means operable at the termination 60 of the aforesaid duplicating operations to render said supplemental control means effective to render said duplicating mechanism ineffective for further duplicating operations.
